UNITED STATES PATENT OFFICE.

CHARLES L. WILLIS, OF RICHMOND, INDIANA.

AUTOMATIC WEATHER AND CARPET STRIP.

Application filed February 28, 1921. Serial No. 448,507.

To all whom it may concern:

Be it known that I, CHARLES L. WILLIS, a citizen of the United States, residing in the city of Richmond, in the county of Wayne, State of Indiana, have invented a new and useful Automatic Weather and Carpet Strip, of which the following is a full, clear, and comprehensive specification and exposition, being such as will enable others to make and install the same with exactitude.

The object of my present invention, broadly speaking, is to provide a weather or carpet strip for doors or the like, having means whereby as the door is closed the space usually below the door, through which cold air, dust, or other elements might enter, will be automatically closed, at the same time providing an assembly which is simple in character, strong and durable in construction, easily installed, and which will require practically no attention to keep it in working condition.

Other minor and subsidiary objects and particular advantages will suggest themselves in the course of the following description, and that which is new will be correlated in the claim.

The preferred means for carrying out my invention in a practical and economical manner is shown in the accompanying drawings, in which—Figure 1 is a front or outside elevation showing my invention in practice in connection with a door, part of which is shown. Figure 2 is a cross section, as taken on the line 2—2 of Fig. 1. Figure 3 is the same as Figure 2 except that the door is shown as partly open thereby changing the position of the invention.

Figure 4 an inside elevation of the door and other related parts and taken from direction opposite to that of Fig. 1. Figure 5 shows the operating finger as taken from two different points. Figure 6 is a cross section of the lower portion of the door alone with related parts removed therefrom. And Figure 7 is a cross section of the central portion of the movable strip alone.

Similar indices denote like parts throughout the several views.

In order that the construction, the operation, and the advantages of my invention may be better understood and appreciated, I will now take up a detailed description thereof, in which I will set forth the various features as fully and as clearly as I may.

Referring now to the drawings in detail: Numeral 1 denotes the door sill, from which extend upwardly the two door-jambs 2 and 3.

Numeral 4 denotes the door, which in this instance is hinged to the jamb 3, as by hinges 5, one of which is shown in dotted lines.

As shown in Figs. 3 and 6 the lower edge of the door 4 is rabbeted to form an outer L-shaped groove, the top A of which is at right angles to the face of the door, and the side B is formed parallel with the face of the door, thereby forming an inside flange C whose lower inner edge is beveled or tapered as at D. Or the edge A may, in fact, be the bottom of the door with the flange C later attached thereto in any well known manner.

Secured on the sill 1, extending between the jambs 2 and 3, and in contact with the inner edges of the jambs 2 and 3, is the permanent strip 6, which forms the minor portion of the weather-strip.

Numeral 7 denotes the movable strip, which forms the major portion of the weather strip, the same extends between the two jambs 2 and 3, and it is movably connected at its forward or outer edge to the face of the sill 1 by means of the hinges 8. The forward or inner edge of the strip 7 is adapted to contact with the strip 6, the two forming an oval weather strip as in Fig. 3.

When the door is closed and the strip 7 is raised, as in Fig. 2, its inner edge contacts with the face A and the side B of the groove in the lower edge of the door, substantially as shown.

A permanent strip forming a hood 11 is secured to the outer face of the door 4, and it adjoins the face A of the groove and it extends the full width of the door to which it is secured.

Cleats 9 and 10 are secured to the opposing faces of the respective jambs 2 and 3 which, when the door is closed, and the strip 7 is lifted up, provide the means for effectually closing the joints at the ends of the strip 7, substantially as shown.

A weight 12 is secured within the central portion of the strip 7 whereby said strip 7 will fall more quickly by gravity whenever it is released, as hereinafter set forth.

Formed across in the strip 6 at a point near its left-hand end, that is in this instance near the jamb 2, is a notch 13, Figure 4.

Numeral 14 denotes an angular finger hav-

ing an eye at its upper end to receive the screw 15 by which said finger is secured to the face B of the groove in the bottom of the door. It will be apparent that as the door 5 is opened and closed the said finger will travel back and forth through the notch 13, whereby the lower portion of said finger may engage the underside of the strip 7, in order to raise said strip 7 as in Fig. 2.

10 It will now be seen that if the door 4 be opened, as in Fig. 3, that the strip 7 will lie flat in contact with the surface of the sill 1 thereby permitting a person to walk thereover or step thereon as in the event of an 15 ordinary carpet strip. However as the door is being closed it is apparent that the finger 14 will project under the strip 7 thereby lifting said strip, and as the door reaches its final closed position the strip 7 will be 20 brought to the position in which it is shown in Fig. 2, thereby absolutely excluding the passage of wind or weather below the door, and thereby accomplishing the desideratum of this invention.

25 Having now fully shown and described my invention, what I claim and desire to secure by Letters Patent of the United States, is—

An automatic weather and carpet strip, in 30 combination with a door-sill and jambs and a door hinged to one of the jambs and adapted to contact with both of the jambs, there

being an L-shaped groove formed in the lower edge of the outer portion of the door, a permanent strip secured on the sill and 35 forming the minor portion of the weather strip, a movable strip forming the major portion of the weather strip and extending between the jambs, hinges by which the movable strip is pivotally connected at its forward outer edge to the face of the sill, the movable strip and the permanent strip being adapted to contact with each other and together to form an oval to close the space between the door and the sill, a hood secured 40 to the outer face of the door to protect the movable strip, cleats secured to the jambs for closing the points at the ends of the weather strip, a weight secured to the movable strip, and an angular finger secured to 45 the face of the groove in the lower edge of the door which as the door is opened and closed will travel back and forth in a notch in the permanent strip whereby the finger may engage or be disengaged from the movable strip, all substantially as shown and described and for the purposes set forth.

In testimony whereof I have hereunto subscribed my name to this specification in the presence of two subscribing witnesses.

CHARLES L. WILLIS.
